SAFETY RAZOR

William Wennmann, Brooklyn, N. Y.

Application December 4, 1936, Serial No. 114,162

6 Claims. (Cl. 30—48)

This invention relates to safety razors in general, and particularly to the type adapted for use with thin double-edged blades.

The prime objects of this invention are to produce a safety razor possessing improved qualities as to shaving, safety in use, and other advantages, while at the same time combining simplicity, ease of manufacture, and inexpensiveness.

Another object of this invention resides in the provision of an arrangement whereby a thin, flexible double-edged blade is caused to assume certain curvatures at its cutting edges simulating the twisted blades of a lawn-mower.

Another important object of this invention is to provide in a safety razor of this kind a cap which projects prominently over the blade surface, whereby the parts to be shaved are brought into a more favorable position in respect to the cutting edge, somewhat simulating the process of the barber shaping the skin for shaving with a straight-edged razor.

A further object of this invention is to provide upon the cap surface suitable means for counteracting adhesion of the razor to the skin.

A still further object of this invention is to provide in a safety razor safety means at the edges of the razor, for covering the end edges of a razor blade so as to prevent the latter from unintentionally injuring the surface to be shaved.

A still further object of this invention is to provide in the guard of such razor, substantial guide means for assuring the proper cooperation between the guard, the cap and the razor blade clamped between these two instrumentalities.

The foregoing and still further objects and other advantages of this invention will become more fully apparent from the ensuing description and the accompanying drawing, which latter, although illustrating the major points of this invention, are not intended to limit the same to the actual showing, and in which

Fig. 1 is a diagrammatical drawing illustrating the flexing and curving of the blade held between the guard and the cap of the present construction;

Fig. 2 is a side elevation of my device in its presently preferred form;

Fig. 3 is an end elevation of my device;

Fig. 4 is a longitudinal sectional view through the device;

Fig. 5 is a longitudinal cross-section through the guard; and

Fig. 6 is a plan view of a typical form of a

blade as used in the safety razor illustrated in Figs. 2, 3, and 4.

Referring now specifically to Fig. 1, numeral 10 denotes a cylinder over which is placed a blade disposed diagonally to the longitudinal axis of the cylinder, and which blade is flexed over the cylinder so that its curvature is substantially that of the cylinder. This blade is indicated at 11, in its different positions. The same blade is illustrated at the lower part of Fig. 1, in its end and side views in which it appears when held between guard and cap.

From the middle part of this figure it will be readily conceivable that an imaginary diagonal cross section through cylinder 10, taken at right angles to the longitudinal center axis of blade 11, or diagonally to the center axis of the cylinder, will correspond to the curvature of an ellipse 12, indicated in broken lines at the lowermost part of Fig. 1, wherein the difference between major and minor axis of the ellipse is very small. The cutting edges of the blade are disposed at angles X to an imaginary horizontal plane 13, passing through the lowermost, diagonally opposite tips of the blade's cutting edges, as illustrated at the right hand lower portion of Fig. 1. This flexing has a great advantage in that when the edges of the blade are brought into cutting position, the blade, so to speak, slices the hair in diagonal direction from one of its ends to the other end, and that the blade actually does not engage the hair on a straight line, but in a manner similar to that of a rotary grass cutter. As a matter of fact, the blade is intended to be "rocked" as it is moved over the surface to be shaved. The incline or angle x of the edges of the blade ranges from 9 to 15 degrees. The device may be manufactured in different styles, wherein the incline of the blade ranges within the limits between 9° and 15°, so that the prospective user may find a design most suitable to his particular condition of hair. I have found that an incline of 12 degrees will suit most conditions.

Referring now to Figs. 2, 3 and 4, the rolling or rocking shaving operation will be more clearly understood by observing the end view of the device shown in Fig. 3, in which it is plainly seen that cap 14, which is substantially cylindrically shaped, extends relatively high above the blade and forces the user of the blade to roll the razor against the skin in order to permit cutting contact of the blade with the beard. This contact is gradual from one end of the blade to the other at each stroke and rolling operation of the razor.

The unusual height of the cap can be clearly seen from the cross-section shown in Fig. 4.

Guard 15 of the razor cooperates with cap 14, in that the interior or adjacent faces of these two members correspond in shape to that of the blade shown in Fig. 1, that is, the interior surfaces of these members are so shaped as to combine a transverse curvature with a longitudinal twist. When a blade is inserted between these two faces and clamped tight, the blade assumes the same form. In order to facilitate the proper clamping of the blade between the two members, cap 14 is provided with guide pins 16 and a central threaded pin 17, all of which pins are disposed in a vertical center plane, indicated at C in Fig. 3, and are parallel to one another. Threaded pin 17 is adapted to be engaged by the internally threaded end of handle 18. Guide pins 16 and central pin 17 pass through suitable, generously dimensioned guides 19 and 20, respectively, provided in the guard member, in order to assure a perfect cooperation between the interior faces of the cap and guard members, thus assuring retention of the intended shape imparted to the flexible blade, while the latter is forcibly held between these two members.

Attention is called to the arrangement of, and the relation between the outer and inner surfaces of cap 14. While the outer cap surfaces is truly cylindrically shaped, as seen from Fig. 3, and prominently extends above its interior, blade-clamping surface, the latter is more complex in its form. This interior cap surface corresponds in shape to an outer surface portion of cylinder 10, which is seen covered by blade 11 in the middle part of Fig. 1. It substantially resembles a rectangle, located diagonally, but symmetrically to the center axis of the cylinder, and is formed by cross sectioning cylinder 10 diagonally and symmetrically to its longitudinal center axis by two pairs of spaced, parallel planes. One pair of planes coincides with the short ends of blade 11, the other pair runs along the long sides or cutting edges of the latter. Both pairs of the planes are perpendicular to the horizontal center plane of cylinder 10.

Furthermore, the vertical center plane C in Fig. 3, which passes through the longitudinal center line of cap 14, cross sections the latter along its thickest and highest body portion, as shown in Fig. 4, and coincides with the longitudinal center line of the inner cap surface, and, consequently with the longitudinal center line of blade 11, which latter center line is disposed diagonally relative to the longitudinal center axis of cylinder 10, as will be observed from the middle part of Fig. 1.

Due to the aforesaid arrangement of parts, the short ends of the blade, when the latter is clamped between the guard and the cap, will be parallel relative to each other, and at right angles to vertical center plane C, as will be evident from consulting Figures 1, 2 and 3, while its cutting edges or long sides, shown in the left-hand lower part of Fig. 1, will be disposed in two parallel planes, which planes are also parallel with vertical center plane C.

Due to the large contacting surface of the cap member, it is necessary to provide therein means for breaking a suctional adhesion between this member and the skin, for which reason there are provided diagonally arranged serrations 21 at both sides of the longitudinal center plane 75 passing through the device, said serrations being

largest at the widest portion of the cap surface and gradually diminishing in size towards the smaller exposed portions, as clearly illustrated in Fig. 2, so as to leave a median longitudinal, smooth, central area, and wherein the direction of the serrations at one side is opposite to the direction of the serrations at the other side, in consequence of the symmetrically opposite arrangement of the sides.

Another important feature of the present invention resides in the provision of end safety guards for preventing unintentional or injurious contact of the end edges or corners of the blade with the skin, for which purpose there are provided lips 22 and 23, extending either from the ends of the cap member or from the ends of the guard or from both, and which end lips are intended to cover either the entire ends or certain portions of the ends of the blade. In Fig. 5 these end guards are shown forming integral extensions of guard member 15, for the purpose of illustrating the principle of the arrangement. It is evident, however, that these end guards may form integral parts of the cap, or may be so arranged that one of the lips, such as end guard 23, may form a part of the cap, whereas the equivalent of end guards 22 may form a part of guard member 15. Inasmuch as such arrangement is obvious, no special illustrations are made of these possible modifications.

In Fig. 6, illustrating a typical form of a blade, the latter is provided with three apertures for receiving guide pins 16 and a central threaded guard and cap connecting pin 17, to which handle 18 is secured, and whereby the cap and guard members are connected with one another. The blade as shown in Fig. 6 is provided with short end extensions which, however, are not required to be present in the event end guards 23 extend over the entire end portions of either the cap 14 or the guard member 15. By the same token, the three apertures illustrated may be substituted by a slot having three enlargements corresponding to the apertures.

While I am aware of the existence of razors with curved razor blades clamped between the guard and cap, I am not aware of any razor construction wherein a razor blade is caused to be both curved and flexed by the two members of the razor, in a manner corresponding to the curvature and flexing obtained when a blade is placed diagonally over a portion of a cylinder, such as provided at the upper face of the guard, as illustrated in Fig. 1, and wherein the diameter of the cylinder, upon which the curvature of the blade depends, is substantially greater than the diameter of the cylinder, indicated in broken lines in Fig. 3, denoting the curvature of cap 14, which latter prominently extends above the guard member, as seen in Fig. 3. Due to this particular curving of the cap, and, due to the flexing of the blade diagonally about a cylindrical formation the shaving advantages are superior in my device over those of any similar devices. Other advantages, such as the disposition of pins 16 and central threaded pin 17, relative to one another and relative to the body of the razor, as well as the generously designed guide means for these pins, of which the central guide means are longer than the outer guide means, and the end safety guards 22 and 23, present considerable improvements over existing mechanisms. The general arrangement of the device permits simple, accurate and inexpensive manufacture, thus rendering quantity produc-

tion of the article not only feasible, but highly advantageous.

While I have shown specific forms of my device in the drawing, it is obvious that changes and improvements may be brought about without departing from the broad scope of my invention, as defined in the annexed claims.

I claim:

1. In a razor holder for double-edged blades, guard and cap members, the adjacent or interior faces of which members have a curvature substantially corresponding to a rectangularly shaped surface portion of a cylinder, disposed diagonally and symmetrically to the longitudinal center axis of the cylinder, the latter having a certain diameter, and wherein the outer face of the cap member prominently extends above its interior face, and its outer surface substantially corresponds to the curvature of a cylinder of lesser diameter, said cap member being provided with guide pins and a central threaded pin, all arranged parallel to one another and disposed in a vertical center plane passing longitudinally through the thickest and highest body portion of said cap member, a plurality of diagonally located serrations, directed in opposite directions at the sides of the outer surface of said cap member, leaving the highest or middle portion thereof smooth, both members being adapted to hold between their adjacent faces a flexible blade and to cause it to assume the curvatures of their interior faces, while the short ends of the blade are kept parallel to one another and at right angles to the vertical center plane, whereas its cutting edges are parallel with the latter, and means, formed at the ends of said members, for guarding the ends of a blade, held between them.

2. In a safety razor, the combination with a double-edged blade, of guard and cap members holding the blade flexed and clamped between them, so that the short ends of the blade are parallel with one another, and at right angles to the vertical center plane passing through the longitudinal center line of the cap member, said blade extending to the parallel end edges of these members, the interior or adjacent faces of said members and of the blade therebetween having the curvature of a diagonally cut cylindrical portion of a certain diameter, the outer surface of said cap member prominently extending above said guard member and substantially corresponding to a diagonally cut cylindrical portion of a lesser diameter and being provided with a plurality of diagonally arranged, oppositely directed serrations at both sides of said member, while the top portion thereof is smooth, the top portion forming the highest and thickest part of the cap member, disposed along the vertical center plane of the latter, and serves for forcing the user to roll the razor while shaving, a plurality of guide means, and guard and cap member connecting means, extending from the interior face of said cap member in the direction of a vertical plane passing longitudinally through said cap member, and guard means arranged at the ends of said members for covering the ends of the blade, and wherein said guard member is provided at its outer or lower surface with a pair of short outer extensions and a relatively long, central extension for accommodating said guide and connecting means, respectively.

ends of said members for covering the ends of the blade.

3. In a safety razor, according to claim 2, and wherein said guard means form integral parts of said guard member.

4. In a safety razor, according to claim 2, and wherein said guard means constitute at each end of the guard member a pair of lips which extend over portions of said cap member.

5. In a safety razor, guard and cap members, a double-edged blade held forcibly therebetween, the interior or adjacent faces of said members substantially corresponding to the curvature of a diagonally cut surface portion of a cylinder of a certain diameter, said cap member projecting prominently above said guard member and its outer surface having substantially the curvature of a cylinder of lesser diameter than that of its interior face, a pair of end pins and a threaded central pin extending from the interior face of said cap member, short end guides and a longer central guide projecting from the outer or lower surface of said guard member, said guides adapted to accommodate said pins, the latter being arranged parallel to one another and in the vertical center plane passing longitudinally through the razor, a plurality of graduated serrations provided at the outer surface of said cap member, and razor-end covering means at the ends of said guard and cap members.

6. In a safety razor, the combination with a double-edged blade, of guard and cap members holding the blade flexed and clamped between them, so that the short ends of the blade are parallel with one another, and at right angles to the vertical center plane passing through the longitudinal center line of the cap member, said blade extending to the parallel end edges of these members, the interior or adjacent faces of said members and of the blade therebetween having the curvature of a diagonally cut cylindrical portion of a certain diameter, the outer surface of said cap member prominently extending above said guard member and substantially corresponding to a diagonally cut cylindrical portion of a lesser diameter and being provided with a plurality of diagonally arranged oppositely directed serrations at both sides of said member, while the top portion thereof is smooth, the top portion forming the highest and thickest part of the cap member, disposed along the vertical center plane of the latter, and serves for forcing the user to roll the razor while shaving, a plurality of guide means, and guard and cap member connecting means, extending from the interior face of said cap member in the direction of a vertical plane passing longitudinally through said cap member, and guard means arranged at the ends of said members for covering the ends of the blade, and wherein said guard member is provided at its outer or lower surface with a pair of short outer extensions and a relatively long, central extension for accommodating said guide and connecting means, respectively.

WILLIAM WENNMAN.
